UNITED STATES PATENT OFFICE

2,187,700

MINING APPARATUS

Edgar M. Cadwallader, Cleveland, Ohio, assignor
to Mineral Cutting Machine Company, Inc.,
Cleveland, Ohio, a corporation of Delaware

Application April 20, 1939, Serial No. 269,001

15 Claims.

(Cl. 255—51)

This invention relates to an apparatus for the mining of coal or similar mineral. More particularly it has to do with the pitch mining of hard coal or similar mineral.

5 In my prior application, Serial No. 153,659, filed July 14, 1937, there is disclosed and claimed an apparatus for the mining of coal or similar mineral which includes means for supporting a combined boring and expansive force inducing element assembly in a vein adjacent the breast or face of coal or similar mineral to be mined and for shifting such assembly either to any desired angular position or raising and lowering such assembly or moving such assembly transversely. The present invention is a modification of such means.

Accordingly, an object of the present invention is to provide a means for supporting the combined boring and expansive force inducing element assembly in a vein adjacent the breast of coal or similar mineral.

Another object of the present invention is to provide a means for shifting the combined boring and expansive force inducing element assembly to a position such that the boring elements are in a horizontal or vertical plane which is at an angle substantially parallel with the pitch of the floor of the vein.

A further object of the present invention is to provide a means for raising and lowering the combined boring and expansive force inducing element assembly in its angular position to any position intermediate the floor and roof of the vein.

35 A still further object of the present invention is to provide a means for moving the combined boring and expansive force inducing element assembly transversely and to any position intermediate the lateral ribs.

40 Other objects and advantages will be apparent as the invention is described in greater detail in connection with the accompanying drawings wherein:

Figure 1 is a side elevation showing the apparatus according to the present invention in operative position in a coal or mineral vein of the pitch type.

Figure 2 is a plan view of the apparatus shown in Figure 1.

50 Figure 3 is an enlarged front elevational view of one of the end supporting brackets.

Figure 4 is an enlarged rear elevational view of one of the cross travel end brackets.

55 Figure 5 is an enlarged vertical diametrical sectional view showing one of the end support-

ing brackets in assembled relation with one of the supporting standards and one of the cross travel end brackets.

Figure 6 is an enlarged elevational view of the upper sleeve supporting bracket.

Figure 7 is a sectional view taken on the line 7—7 of Figure 8.

Figure 8 is a sectional view taken on the line 8—8 of Figure 7.

Figure 9 is a sectional view taken on the line 9—9 of Figure 2.

Figure 10 is a sectional view taken on the line 10—10 of Figure 9.

Referring to Figures 1 and 2, the numeral 1 designates a housing from which protrude a series of spaced and aligned boring elements 250, said elements being rotatably mounted within said housing. Associated with such boring elements are expansive force inducing elements but since they form no part of the present invention, they are not shown. A casing 18 encloses a gear mechanism, and a tubular member or sleeve 42 which encloses the actuating mechanism connecting said boring elements to said gear mechanism is interposed between the housing 1 and casing 18.

As shown in Figure 1, a supporting sleeve 165 surrounds the tubular member or sleeve 42 and is secured to the transmission casing 18. Securely mounted upon sleeve 42 and suitably spaced from the sleeve 165 is a second supporting sleeve 165' which comprises supporting brackets 166 and 167. As the structure of these brackets is the same, only one will be described in detail. The bracket 166, as shown in Figures 1 and 6, has a semicircular portion or section 168 which surrounds the upper half portion of the sleeve 42 and apertured ears or lugs 169 and 170 projecting from said portion 168. Tubes 171, Figures 1 and 2, extend transversely through the lugs 169 and 170 and are supported in cross travel end brackets 172. It will be apparent, however, that there are also two tubes 171 which extend through the other bracket 167 and are likewise supported in the brackets 172.

By reference to Figures 1 and 2, it will be seen that there are a plurality of trolley wheels 173 mounted for travel along the tubes 171, the said trolley wheels being carried by the supporting brackets 166 and 167 comprising the sleeve 165'. Each of the trolley wheels 173, Figures 6, 7, and 8, is rotatably mounted on a pin 174 carried by a trolley bracket 175. The trolley bracket 175 is provided with a plurality of slotted openings 176 which may be moved into complementary re-

lation with any one of the openings 177 in either of the lugs 169 and 170, and the bracket 175 and lug 169 or 170 locked together by means of a bolt 178. As shown in Figure 1, the rollers designated by the letters B and D are positioned so that they will straddle the top surface of the tubes 171 while the rollers designated by the letters A and C are positioned so that they will bear upon the tubes 171 at an angle to the horizontal. By this arrangement the rollers B and D support the weight of the combined boring and expansive force inducing element apparatus, and the rollers A and C act to counteract the back pressure caused by the action of the boring elements while working in the breast of coal or mineral.

The cross travel end brackets 172, Figure 2, are rotatably mounted on end supporting brackets 179 which are movable upon each of the supporting standards 240. The brackets 172, Figure 3, are provided with a plurality of slotted openings 180 which may be moved into complementary relation with any one of the openings 181 in the end supporting bracket 179, Figure 4, and the brackets 172 and 179, Figure 5, locked together by means of bolts 182.

The supporting standards 240, Figures 1, 2, and 5, are provided with toothed racks 183. Each of the racks 183 is in meshing engagement with a gear 184, Figures 9 and 10, carried by a shaft 185. Fixedly mounted upon the shaft 185 and suitably spaced from the gear 184 is a worm 186 which is in mesh with a worm 187 carried by a shaft 188 provided with a squared free end 189 for the reception of a suitable wrench for rotating the shaft 188 in either desired direction. The brackets 179 also carry guide wheels 190, Figure 2, which ride upon the smooth under surface of the toothed racks 183.

Referring to Figures 1 and 2, the supporting bracket 166 of the sleeve 165 carries a reversible motor 191 which rotates a pinion 192. The pinion 192 meshes with a toothed rack 193 carried by a transversely extending tube 194 which is supported by and secured to cross travel end brackets 172. By this mechanism the combined boring and expansive force inducing apparatus is moved back and forth transversely across the face or breast of coal or mineral.

The top ends of the supporting standards 240, Figures 1 and 2, are connected to side I beams 200 and 201 disposed adjacent the ceiling of the vein by means of brackets 202. The lower ends of the supporting standards 240 are connected to side I beams 205 and 206 of the carriage 207 by means of brackets 208. The side I beams 205 and 206 also carry brackets 209 to which are connected the lower ends of telescopic supports 210 and 211. The upper ends of each of the telescopic supports 210 are connected to the brackets 213 carried by the side I beams 200 and 201, and the upper ends of each of the telescopic supports 211 are connected to brackets 212 also carried by the side I beams 200 and 201. Extending transversely between the side I beams 200 and 201 are I beam tracks 216 which are connected thereto by means of brackets 217.

The carriage 207, Figures 1 and 2, is provided with wheels 218 which ride along tracks 219 longitudinally disposed along the floor of the vein. The wheels 218 are connected to the side I beams 205 and 206 by means of brackets 220 and 221. The tracks 219 set in boots 222 and 223, and are fixedly secured thereto. To the sides of each of the boots 222 and 223 are se-

cured yokes 224 to which are attached the lower ends of telescopic tubes 225. The upper ends of the telescopic tubes engage with the ceiling of the vein and are anchored thereto by means of claw shaped shoes 226. Jacks 228 are mounted on I beams 205 and 206 for moving the carriage 207 along the tracks 219. The tracks 219 are provided with means for locking the carriage 207 at the stopping position, such means comprising a dog 233 carried by the side I beams 205 and 206 which engages with a toothed rack 236 fixedly secured to the top of the tracks 219.

In operation of the apparatus according to the present invention, the tubular member or sleeve 42 is shifted to a position such that the boring elements will be in a horizontal plane which is at an angle substantially parallel with the pitch of the floor of the vein. This is done by removing the bolts 182, rotating the cross travel end brackets 172 in the direction such that the proper one of the openings 181 is brought into registry with the slotted opening 180 corresponding to the position to which the tubular member has been moved, then inserting the bolts 182 through the registering pair of openings 181 and 180, and locking the brackets 172 and 179 in their aligned position by turning down the nut on the bolts 182.

To raise or lower the tubular member 42 so that the boring elements will be in a position intermediate the roof and floor of the vein, a wrench is placed upon the squared end 189 of the shaft 188 and such shaft rotated in the proper direction until the boring elements have been raised or lowered to the desired extent. The rotation of the shaft 188 causes the gear 184 to travel upwardly or downwardly along the toothed racks 183 through the medium of worm 187, worm 186 and shaft 185.

To shift the tubular member 42 transversely so that the boring elements will be at a position to attack a multiple of the working breast extending from either the right or left hand lateral ribs or intermediate said ribs, the reversible motor 191 is actuated in the proper direction to effect movement of the tubular member to the right or left. The actuation of such motor causes the pinion 192 to travel along the toothed rack 193 to the right or left depending upon the direction in which the motor shaft is rotated.

Having thus described the invention, what is claimed as new and desired to be secured by Letters Patent is:

1. In an apparatus for the mining of coal or similar mineral, a housing, a plurality of rotatable boring elements arranged in spaced and aligned relation mounted in said housing and having an end extended through a wall thereof, a casing enclosing a gear mechanism, a tubular member enclosing the actuating mechanism connecting said boring elements to said gear mechanism interposed between said housing and said casing, a supporting sleeve surrounding said tubular member, supporting standards, a supporting bracket surrounding each of said standards and carried thereby, a second supporting bracket disposed adjacent to each of said first named supporting brackets, tubes extending transversely between said second named supporting brackets and carried thereby, and trolleys carried by said sleeve and mounted for travel along each of said tubes whereby the boring elements as a unit are supported in the breast at an angle substantially parallel with the pitch of the floor of the vein.

2. In an apparatus for the mining of coal or similar mineral, a housing, a plurality of rotatable boring elements arranged in spaced and aligned relation mounted in said housing and having an end extended through a wall thereof, a casing enclosing a gear mechanism, a tubular member enclosing the actuating mechanism connecting said boring elements to said gear mechanism interposed between said housing and said casing, a supporting sleeve surrounding said tubular member, supporting standards, a supporting bracket provided with a plurality of openings surrounding each of said standards and carried thereby, a second supporting bracket disposed adjacent to each of said first named supporting brackets, tubes extending transversely between said second named brackets and carried thereby, trolleys carried by said sleeve and mounted for travel along each of said tubes, each of said second named supporting brackets being provided with a plurality of openings therealong and movable so that any one of its openings may be shifted into complementary relation with an opening in each of said first named supporting brackets to thereby shift said boring elements as a unit to a position such that they are at an angle substantially parallel with the pitch of the floor of the vein, and means for locking said second named and first named supporting brackets in their aligned complementary relation.
3. In an apparatus for the mining of coal or similar mineral, a housing, a plurality of rotatable boring elements arranged in spaced and aligned relation mounted in said housing and having an end extended through a wall thereof, a casing enclosing a gear mechanism, a tubular member enclosing the actuating mechanism connecting said boring elements to said gear mechanism interposed between said housing and said casing, a supporting sleeve provided with apertured lugs surrounding said tubular member, supporting standards, a supporting bracket surrounding each of said standards and carried thereby, a second supporting bracket disposed adjacent to each of said first named supporting brackets, tubes extending transversely between said second named supporting brackets and carried thereby, a trolley bracket secured to each of said apertured lugs, and a trolley wheel carried by each of said trolley brackets and mounted for travel along each of said tubes whereby the boring elements as a unit are supported in the breast at an angle substantially parallel with the pitch of the floor of the vein.
4. In an apparatus for the mining of coal or similar mineral, a housing, a plurality of rotatable boring elements arranged in spaced and aligned relation mounted in said housing and having an end extended through a wall thereof, a casing enclosing a gear mechanism, a tubular member enclosing the actuating mechanism connecting said boring elements to said gear mechanism interposed between said housing and said casing, a supporting sleeve provided with apertured lugs on its sides surrounding said tubular member, supporting standards, a supporting bracket surrounding each of said standards and carried thereby, a second supporting bracket disposed adjacent to each of said first named supporting brackets, tubes extending transversely between said second named supporting brackets and carried thereby, a trolley bracket secured to each of said apertured lugs, and a trolley wheel carried by each of said trolley brackets being provided with a plurality of openings therealong and movable so that any one of its openings may be shifted into complementary relation with an opening in each of said first named supporting brackets to thereby shift said boring elements as a unit to a position such that they are at an angle substantially parallel with the pitch of the floor of the vein, and means for locking said second named and first named supporting brackets in their aligned complementary relation.
5. In an apparatus for the mining of coal or similar mineral, a housing, a plurality of rotatable boring elements arranged in spaced and aligned relation mounted in said housing and having an end extended through a wall thereof, a casing enclosing a gear mechanism, a tubular member enclosing the actuating mechanism connecting said boring elements to said gear mechanism interposed between said housing and said casing, a supporting sleeve provided with apertured lugs on its sides surrounding said tubular member, supporting standards, a supporting bracket surrounding each of said standards and carried thereby, a second supporting bracket disposed adjacent to each of said first named supporting brackets, tubes extending transversely between said second named supporting brackets and carried thereby, a trolley bracket secured to each of said apertured lugs, each of said trolley brackets being provided with a plurality of openings therealong and movable so that any one of its openings may be shifted into complementary relation with an opening in each of said first named supporting brackets to thereby shift said boring elements as a unit to a position such that they are at an angle substantially parallel with the pitch of the floor of the vein.
6. In an apparatus for the mining of coal or similar mineral, a housing, a plurality of rotatable boring elements arranged in spaced and aligned relation mounted in said housing and having an end extended through a wall thereof, a casing enclosing a gear mechanism, a tubular member enclosing the actuating mechanism connecting said boring elements to said gear mechanism interposed between said housing and said casing, a supporting sleeve provided with apertured lugs on its sides surrounding said tubular member, supporting standards, a supporting bracket surrounding each of said standards, and carried thereby, a second supporting bracket disposed adjacent to each of said first named supporting brackets, tubes extending transversely between said second named brackets and carried thereby, a trolley bracket secured to each of said apertured lugs, and a trolley wheel carried by each of said trolley brackets and mounted for travel along each of said tubes, each of said second named supporting brackets being provided with a plurality of openings therealong and movable so that any one of its openings may be shifted into complementary relation with an opening in each of said first named supporting brackets to thereby shift said boring elements as a unit to a position such that they are at an angle substantially parallel with the pitch of the floor of the vein, and means for locking said second named and first named supporting brackets in their aligned complementary relation.
7. In an apparatus for the mining of coal or similar mineral, a housing, a plurality of rotatable boring elements arranged in spaced and aligned relation mounted in said housing and

necting said boring elements to said gear mechanism interposed between said housing and said casing, a supporting sleeve surrounding said tubular member, supporting standards, a supporting bracket surrounding each of said standards and carried thereby, a second supporting bracket disposed adjacent to each of said first named supporting brackets, tubes extending transversely between said second named supporting brackets and carried thereby, trolleys carried by said sleeve and mounted for travel along each of said tubes whereby the boring elements as a unit are supported in the breast at an angle substantially parallel with the pitch of the floor of the vein, means for raising and lowering said tubular member to thereby shift the boring elements while in their adjusted angular position to any position intermediate the roof and floor of the vein, and means for shifting the tubular member transversely to thereby shift the boring elements while in their adjusted position to any position intermediate the lateral ribs.

13. In an apparatus for the mining of coal or similar mineral, a housing, a plurality of rotatable boring elements arranged in spaced and aligned relation mounted in said housing and having an end extended through a wall thereof, a casing enclosing a gear mechanism, a tubular member enclosing the actuating mechanism connecting said boring elements to said gear mechanism interposed between said housing and said casing, a supporting sleeve surrounding said tubular member, supporting standards, each of said standards being provided with a toothed rack on its upper face, a supporting bracket surrounding each of said standards and carried thereby, a second supporting bracket disposed adjacent to each of said first named brackets, tubes extending transversely between said second named supporting brackets and carried thereby, trolleys carried by said sleeve and mounted for travel along each of said tubes whereby the boring elements as a unit are supported in the breast at an angle substantially parallel with the pitch of the floor of the vein, a gear in meshing engagement with each of said toothed racks, gearing carried by each of said first named supporting brackets connected to each of said gears to thereby shift the boring elements while in their adjusted angular position to any position intermediate the roof and floor of the vein, and means for shifting the tubular member transversely to thereby shift the boring elements while in their adjusted position to any position intermediate the lateral ribs.

14. In an apparatus for the mining of coal or similar mineral, a housing, a plurality of rotatable boring elements arranged in spaced and aligned relation mounted in said housing and having an end extended through a wall thereof, a casing enclosing a gear mechanism, a tubular member enclosing the actuating mechanism connecting said boring elements to said gear mechanism interposed between said housing and said casing, a supporting sleeve surrounding said tubular member, supporting standards, each of said standards being provided with a toothed rack on its upper face, a supporting bracket surrounding each of said standards and carried thereby, a second supporting bracket disposed adjacent to each of said first named brackets, tubes extending transversely between said second named supporting brackets and carried thereby, trolleys carried by said sleeve and mounted for travel along each of said tubes whereby the boring elements as a unit are supported in the breast at an angle substantially parallel with the pitch of the floor of the vein, a gear in meshing engagement with each of said toothed racks, gearing carried by each of said first named supporting brackets connected to each of said gears to thereby shift the boring elements while in their adjusted angular position to any position intermediate the roof and floor of the vein, a transversely disposed toothed rack supported by said second named supporting brackets, a gear in meshing engagement with said rack, and actuating mechanism carried by said supporting sleeve connected to said last named gear to thereby shift the boring elements while in their adjusted position to any position intermediate the lateral ribs.

15. In an apparatus for the mining of coal or similar mineral, a housing, a plurality of rotatable boring elements arranged in spaced and aligned relation mounted in said housing and having an end extended through a wall thereof, a casing enclosing a gear mechanism, a tubular member enclosing the actuating mechanism connecting said boring elements to said gear mechanism interposed between said housing and said casing, a supporting sleeve surrounding said tubular member, supporting standards, each of said standards being provided with a toothed rack on its upper face, a supporting bracket surrounding each of said standards and carried thereby, a second supporting bracket disposed adjacent to each of said first named brackets, tubes extending transversely between said second named supporting brackets and carried thereby, trolleys carried by said sleeve and mounted for travel along each of said tubes whereby the boring elements as a unit are supported in the breast at an angle substantially parallel with the pitch of the floor of the vein, a gear in meshing engagement with each of said toothed racks, gearing carried by each of said first named supporting brackets connected to each of said gears to thereby shift the boring elements while in their adjusted angular position to any position intermediate the roof and floor of the vein, a transversely disposed toothed rack supported by said second named supporting brackets, a gear in meshing engagement with said last named rack, and actuating mechanism carried by said supporting sleeve connected to said last named gear to thereby shift the boring elements while in their adjusted position to any position intermediate the lateral ribs.

EDGAR M. CADWALLADER.
